CLAIM

I claim the ornamental design for a flip-flop cell phone holder, as shown.

DESCRIPTION

FIG. 1 is a top view of a first embodiment of a flip-flop cell phone holder showing my new design;

FIG. 2 is a bottom view of the embodiment of FIG. 1;

FIG. 3 is a perspective view from the left side of the embodiment of FIG. 1;

FIG. 4 is a perspective view from the right side of the embodiment of FIG. 1;

FIG. 5 is a perspective view from the front side of the embodiment of FIG. 1;

FIG. 6 is a perspective view from the rear side of the embodiment of FIG. 1;

FIG. 7 is a top view of an embodiment of FIG. 1 incorporating a first decorative attachment shown in phantom;

FIG. 8 is a top view of an embodiment of FIG. 1 incorporating a second decorative attachment shown in phantom;

FIG. 9 is a top view of an embodiment of FIG. 1 incorporating a third decorative attachment shown in phantom;

FIG. 10 is a top view of an embodiment of FIG. 1 incorporating a fourth decorative attachment shown in phantom;

FIG. 11 is a top view of an embodiment of FIG. 1 incorporating a fifth decorative attachment shown in phantom;

FIG. 12 is a top view of an embodiment of FIG. 1 incorporating a sixth decorative attachment shown in phantom; and,

FIG. 13 is a top view of an alternate embodiment of a flip-flop cell phone holder showing my new design. The bottom, side, front and rear views of this embodiment are the same as those views of the first embodiment.

The broken line showing of environment in the drawings is included for the purpose of illustrating only and forms no part of the claimed design.
